UNITED STATES PATENT OFFICE.

JOHN R. MILLAR, OF OAKLAND, CALIFORNIA, ASSIGNOR TO CALIFORNIA COTTON MILLS COMPANY, OF OAKLAND, CALIFORNIA, A CORPORATION OF CALIFORNIA.

UPHOLSTERY MACHINE.

Application filed June 25, 1923. Serial No. 647,511.

My invention is an improvement in the method of manufacturing a padding, and the machine to form it.

The invention relates particularly to the padding which is used in automobile seats. The method now employed is to form each separate seat padding into a plurality of padding receiving pockets after which the padding is inserted into said pockets. This 10 method is very slow and requires a large amount of labor.

The object of my invention is to provide a machine in which the completed seat, or back, is formed in an endless strip, with the 15 pockets formed and the padding material in position in said pockets. This is accomplished by forming the seat into longitudinal tubes over forming rollers, simultaneously inserting the padding in said tubes, and 20 stitching the seat between these tubes, thus holding it in position. The padded back or seat strip thus formed is afterwards cut into any desired length for the individual seat or back.

25 Another object of my invention is to place a horizontal stitch between the tubes, thus giving the back greater strength in the stitches than is possible in the ordinary chain or vertical stitch.

Further objects and advantages will be more specifically described and pointed out in the following detailed description.

In the annexed drawing in which my invention is illustrated, I have shown the preferred form but it may also be embodied in other forms, and in this application I desire to cover my invention in whatever form it may be embodied.

Figure 1 is a side elevation of my padding 40 machine.

Figure 2 is a sectional view taken on the line 2—2 of Figure 1.

Figure 3 is a sectional view taken on the line 3—3 of Figure 1.

45 Figure 4 is a fragmentary longitudinal sectional view through the intake or forming rollers.

Referring more particularly to the drawing, the numeral 1 indicates the base of my machine, upon which the various rolls and tables are mounted. If we take for example a seat or back in which there are twelve pockets in width filled with padding, then twelve rolls of padding 2 are mounted upon 50 a shaft 3, which is supported on brackets 4

rising from the base 1. A roll of surface material 5, such as leather, cloth, etc. of sufficient width to form the twelve pockets, is mounted upon supports 6—6 which rise from the base 1.

60 A roll of backing material 7, such as burlap, and of sufficient width to cover the back of the pockets, is mounted upon supports 8—8.

A pair of superimposed forming rollers 9 and 10 are mounted forwardly of the rolls 2, 5 and 7, and are journaled in the supports 11—11. As here illustrated only three pockets are formed in the rollers 9 and 10, but it is understood that any desired number may be formed by increasing the width of said rollers. The lower roller 10 has a plurality of deep grooves 12 formed therein which conform in shape to the pockets in the seat. The ridges 13 between the grooves 12 are adapted to enter shallow grooves 14 in the roller 9.

70 A plurality of tubes 15, are supported from the supports 8 and extend forwardly through the rollers 9 and 10, one tube extending through each of the grooves 12. Each of these tubes are spaced above the bottom of the grooves 12 a distance equal to the thickness of the material on the roll 5, and the bottom of the roller 9, is spaced above the top of the tubes the thickness of the burlap on roll 7. The tubes 15 extend beyond the rollers 9 and 10 and into the grooves 16 of a forming table 17. The table 17 is formed similar to the roller 10, and 80 holds the material in shape as it is fed into the stitching device. Ridges 18 are formed between the grooves 16 in alignment with the ridges 13 on the roller 10.

90 Immediately in front of the table 17 is positioned the stitching machine 19, which is of a well known construction, and places a horizontal stitch through the surface and back material between the pockets. The machine is provided with pairs of needles 20 which carry the stitch as described.

100 Forwardly of the machine 19 are positioned a pair of feed rollers 21 and 22, which are journaled in supports 23—23 and are suitably driven through a chain 24 which 105 extends over a sprocket 25 on the shaft of the roller 22. The rollers 21 and 22 pull the material through the machine and eject it therefrom at a constant speed.

110 The operation of my machine is as fol-

lows: A strip of padding is fed through each of the tubes 15. The surface material from the roll 5 is threaded under the tubes 15 in the grooves 12 in the roller 10 and in the grooves 16 in the table 7. The ridges 13 and 18 form an upwardly projecting tongue in the material. The burlap is fed through the machine over the tubes 15 and the ridges 13 and 18 and grooves 14 form it over the 10 tongues in the surface material ready to be stitched thereto by the machine 19. The padding completely fills the pockets thus formed and the sewing machine sews the tongues together as described, which forms 15 the seat or back complete. The padded seat or back coming out of the machine in an endless strip is cut into suitable lengths for the individual seats.

If it is desired to have a flat backed padding with the stitches between the bottom and the top instead of through the ridges, the meeting surfaces of the lower and upper rollers would be shaped so as to guide the surface and backing materials to a suitable 25 type of sewing machine. In this case the grooves 14 of the upper roller could be eliminated and the engaging ridges 13 on the roller 10 flattened to contact with a flat surface.

30 Having described my invention I claim:
1. A padding machine comprising two forming rollers, one of said rollers having deep grooves therein separated by ridges, and the other of said rollers being provided 35 with shallow grooves adapted to receive the crests of said ridges, a tube extending through each of said deep grooves, and means whereby a backing material and a sur-

face material are caused to pass through said deep and shallow grooves, said means 40 also being adapted to pull a padding strip through each of said tubes and between the backing and surface materials.

2. In a padding machine, a plurality of 45 rollers, one of said rollers having shallow grooves therein, the other of said rollers having deep grooves separated by ridges, the crests of the ridges extending into the shallow grooves of the first mentioned rollers, and tubes extending through said deep 50 grooves.

3. A padding machine comprising a plurality of rollers, one of said rollers being provided with deep grooves, a table having 55 grooves therein corresponding with the grooves in the roller and in alignment with the same, and tubes extending through said deep grooves in the roller and terminating within the grooves in the table.

4. A padding machine comprising a plurality of rollers, one of said rollers being provided with deep grooves, a table having grooves therein corresponding with the grooves in the roller and in alignment therewith, and tubes extending through said deep 60 grooves in the roller and terminating within the grooves in the table, and means whereby a strip of surface material and a strip of 65 backing material are caused to pass around said tube, said means also serving as a means to simultaneously pull a strip of padding through each of said tubes.

In testimony whereof I affix my signature.

JOHN R. MILLAR.
